(57) **CLAIM**

The ornamental design for a golf club head, as shown and described.

DESCRIPTION

FIG. 1 is a top perspective view of a golf club head according to a first embodiment;
FIG. 2 is a bottom perspective view of the golf club head of FIG. 1;
FIG. 3 is a front elevational view of the golf club head of FIG. 1;
FIG. 4 is a rear elevational view of the golf club head of FIG. 1;
FIG. 5 is a top view of the golf club head of FIG. 1;
FIG. 6 is a bottom view of the golf club head of FIG. 1;
FIG. 7 is a left side view of the golf club head of FIG. 1;
FIG. 8 is a right side view of the golf club head of FIG. 1;
FIG. 9 is a top perspective view of a golf club head according to a second embodiment;
FIG. 10 is a bottom perspective view of the golf club head of FIG. 9;
FIG. 11 is a front elevational view of the golf club head of FIG. 9;
FIG. 12 is a rear elevational view of the golf club head of FIG. 9;
FIG. 13 is a top view of the golf club head of FIG. 9;
FIG. 14 is a bottom view of the golf club head of FIG. 9;
FIG. 15 is a left side view of the golf club head of FIG. 9;
and,
FIG. 16 is a right side view of the golf club head of FIG. 9.
The broken lines shown on the drawings form no part of the claimed design.

1 Claim, 8 Drawing Sheets

Related U.S. Application Data

which is a continuation-in-part of application No. 29/754,405, filed on Oct. 9, 2020, which is a continuation-in-part of application No. 29/745,977, filed on Aug. 11, 2020, now abandoned.
